UNITED STATES PATENT OFFICE.

ALBERT BERNARD WEISSENBORN, OF APPLETON, WISCONSIN, ASSIGNOR OF ONE-HALF TO APPLETON WIRE WORKS, OF APPLETON, WISCONSIN.

LET-OFF MECHANISM.

1,391,435.

Specification of Letters Patent. Patented Sept. 20, 1921.

Application filed July 16, 1918. Serial No. 245,170.

To all whom it may concern:

Be it known that I, ALBERT B. WEISSENBORN, a citizen of the United States, and resident of Appleton, Outagamie county, Wisconsin, have invented new and useful Improvements in Let-Off Mechanism, of which the following is a description, reference being had to the accompanying drawings, which are a part of this specification.

10 This invention relates to let-off mechanism for looms, particularly wire-weaving looms such as looms for weaving Fourdrinier wires, and has for its object to automatically reposition the tension lever connection with the warp beam as the wire is drawn off of the latter so as to maintain a predetermined tensioning effect on the warp wires.

Another object for the invention is to utilize the oscillation of the tension lever incident to the operation of the loom to control a power means for letting off the warp wires by changing the position of the connection of the tension lever with the warp beam.

25 Another object of the invention is to provide synchronously operated adjusting means at both ends of the warp beam.

Another object of the invention is to vary the degree of readjustment accomplished by 30 the operation of the power means to suit the requirements of fabrics of different mesh.

With the above and other objects in view the invention consists in the let-off mechanism as herein claimed and all equivalents.

35 Referring to the accompanying drawings, in which like characters of reference indicate the same parts in different views:

Figure 1 is a side view of a loom provided with the automatic let-off mechanism 40 of this invention;

Fig. 2 is an enlarged view of the let-off mechanism;

Fig. 3 is a front view of the warp beam with the let-off mechanism applied thereto;

45 Fig. 4 is a sectional detail view of the power-operated means for turning the worm shaft;

Fig. 5 is a sectional plan view thereof; and,

50 Fig. 6 is a detail view of the air valve.

In these drawings 10 indicates the side frames of the loom between which are mounted the warp-beam 11, the breast-beam 12 and receiving-roll 13, as usual. The

swinging lay 14 operates as usual to beat 55 up the weft wire left by the shuttle in its travel through the shed formed between the warp wires 15 by the alternate reciprocation of the heddles, and suitable means is provided for operating the receiving roll 13 60 to wind the fabric thereon as it is woven.

Tension is given to the warp wires 15 by means giving the warp beam 11 a tendency to turn backwardly or in a direction to rewind the wires thereon and it is this tension 65 means, capable of changing its point of connection with the warp beam to permit the wires being unwound therefrom without materially varying the tension, that constitutes the present invention. 70

At each end of the shaft 16 of the warp beam 11 is fixed a worm wheel 17, and each worm wheel meshes with a worm 18 on a vertical shaft 19 slidably mounted in suitable bearings and having swivel connection 75 with a block 20 pivotally mounted between a pair of links 21 suspended from a lever 22 which is fulcrumed at 23 on the frame. Each of the levers 22 has a link connection 24 with a tension lever 25 fulcrumed at 26 80 on the frame and provided with adjustable weights 27 acting through said links 24, levers 22, links 21, blocks 20 and shafts 19 to lift the worms 18 and thereby turn the worm wheels 17 and the warp beam 11 backwardly to tighten the wires forming the shed. 85

The vertical shafts 19 are provided with the swivel connections in order that they may be turned for feeding the worms 18 to 90 different points of engagement with the worm wheels 17.

Loosely mounted in the lower bearing 28 of each shaft 19 is a sleeve 29 splined on the shaft 19, permitting the shaft to freely slide 95 within it but compelling it to turn therewith. A projection 30 on the bearing entering a groove of the sleeve holds the sleeve against vertical displacement.

A bell crank 31, fitting in another groove 100 of the sleeve 29, carries a spring-pressed pawl 32 on one arm to engage the teeth of a ratchet disk 33 formed on or secured to the sleeve 29. The other arm of the bell crank 31 has an upstanding stud 34 and a connecting rod 35 connects the stud 34 on one side of the loom with the corresponding stud 34 on the other side of the loom so that both 105

of the bell cranks move together for producing the same effect at both ends of the warp beam.

On one of the bearings 28 is a bracket 36 supporting a cylinder 37 in which there is a piston 38 connected by a connecting rod 39 with the upstanding stud 34 of the bell crank. It is under the influence of pressure fluid, such as compressed air, in the cylinder 37 that the piston serves to swing both bell cranks 31 to turn the shafts 19 through the engagement of the pawls with their ratchets. The return movements are caused by a coil spring 40 connected with the connecting rod 35 and with a stationary support. The degree of movement of the bell cranks 31 with each operation may be varied by the turning of an adjusting screw 41 forming a stop for engaging one arm of one of the bell cranks 31 and forming a stop therefor. This set screw 41 is threaded through a removable post 42 which may be changed in its position on the bearing by placing it in another opening 43 thereof to increase the range of adjustability.

For automatically controlling the supply of compressed air or other pressure fluid to the cylinder 37, a roller 44 projecting from lever 22 is adapted in its downward movement to engage a roller 45 on one arm of a bell crank 46 fulcrumed on the frame 10. The other arm of the bell crank 46 is connected by a valve rod 47 with a valve on the cylinder 37. The valve construction, which is best seen in Figs. 4 and 6, comprises a casting 48 forming a valve chamber with a valve seat between a port 49 leading to the interior of the cylinder and a port communicating with a compressed air supply pipe 50. A spring-pressed valve member 51 is seated on the valve seat and has a tubular stem 52 projecting therefrom and passing through a packing gland in the bottom of the valve casing. The tubular valve stem 52 has an opening at its upper end communicating with the passageway 49 to the cylinder, and through this opening and the bore of the stem the air is exhausted from the cylinder when the valve is closed.

At the lower end of the valve rod 47 is a yoke 53 passing around the valve casing and forming a seat at its lower end for a member 54 which has a spherical self-centering base portion resting on the seat and a stem 55 passing downwardly through an opening in the seat. This member is tubular at its upper portion or cup-shaped to fit around the tubular valve stem 52 and form a telescoping connection therewith. A leather plug or other valve material 56 is contained in the bottom of the cup-like socket of member 54 to form a tight-fitting connection with the end of the tubular stem and prevent the passage of air therethrough when the yoke 53 is lifted by the valve rod for unseating the

valve. A vent opening 57 in the member 54 permits the outlet of the exhaust air when the valve is seated and the valve face 56 is moved away from the end of the stem 52.

In operation the warp wires forming the shed are given the proper tension by the action of the weight 27 tending to lift the worm 18 by means of the lever 22 and thus imparting a tendency to the warp beam to turn backwardly. As the wire is drawn off of the warp beam during the operation of the loom this tendency has to be overcome and the worm with its shaft 19 is moved downwardly, causing the weight to rise. At a certain point in the travel of these parts the roller 44 on lever 22 engages the roller 45 on bell crank 46 causing the valve rod to be lifted until it unseats the valve 51. This admits compressed air to the cylinder 37, while the exhaust is closed by the engagement of the valve face 56 with the end of the tubular valve stem 52, and consequently the piston 38 is moved outwardly causing both bell cranks 31 to swing and feed the ratchet disks and the shafts 19 a distance determined by the position of the stops 41. Such turning of the shafts 19 threads the worms 18 to higher positions on the worm wheels of the warp beam without interrupting the tensioning. This upward movement of the shafts 19 causes a corresponding lowering of the weights 27 and also causes the disengagement of the rollers 44 and 45 permitting the air valve to again close and opening the exhaust from the cylinder so that spring 40 restores the bell cranks 31 to their original positions ready for the next feeding operation.

The degree of movement of the various parts is not great, for the worms are only given a fractional turn with each operation. Under normal conditions when the lay carrying the reed beats up a weft wire, the concussion causes lever 22 to momentarily drop. It is this momentary depression which is used to accomplish the governing of the tension device. Under normal weaving when the shed is open, the lever 22 is depressed slightly but possibly not enough for the accomplishment of the let-off regulation, but when the blow is struck the depression of lever 22 is sufficient to cause the opening of valve 51 and an operation of the piston, producing a let-off.

One important feature of this invention is that the tension lever 25 is always maintained in an approximately horizontal position to maintain the tension approximately uniform.

In weaving fabric of different mesh it is necessary to adjust the let-off so that it will let off more warp than is needed. It is practically impossible to get a sufficiently even adjustment so as to let off the exact amount required. Various causes influence the

amount of warp wire required for a given length of fabric of a certain mesh. If the weft wire differs a little in temper it will take up more or less warp. Another reason 5 is that when a new wire is started, and as the weaving progresses, the woven cloth piles up on the receiving-roll so that there must be some method of compensating for the difference between a wire with one lap 10 on the receiving-roll and one with the diameter increased by six or eight laps. To compensate for this difference the let-off is adjusted by means of the stop screw 41 to let off more than is necessary so that with every 15 sixth or eighth weft wire laid the let-off device does not act, the cumulative surplus feeding movement of the worms having raised the lever 22 so far that the oscillating or dancing movement thereof incident to 20 the blow of the reed does not produce the necessary engagement of the rollers 44 and 45 for the operation of the let-off.

In accordance with the provisions of the patent statutes I have described the principle of operation of my invention together 25 with the apparatus which I now consider to represent the best embodiment thereof; but I desire it to be understood that the apparatus shown is only illustrative, and that 30 the invention can be carried out by other means within the scope of my claims.

What I claim as new and desire to secure by Letters Patent is:

1. In a loom, a warp beam, a tension lever 35 having connection therewith for turning same backwardly, and means actuated by the play of the tension lever for varying the connection between the tension lever and the warp beam to produce a let off.

2. In a loom, a warp beam, a tension lever 40 having connection therewith, and fluid pressure-operated means for varying the connection between the tension lever and the warp beam for producing a let off, said means being actuated by the movement of the tension lever.

3. In a loom, a warp beam, a tension lever 45 having connection therewith, a trigger in the path of the tension lever, and fluid pressure-operated means controlled by the trigger for changing the connection between the tension lever and the warp beam for producing a let off.

4. In a loom, a warp beam, a tension lever 55 having connection with the warp beam, means for adjusting the connection between the tension lever and the warp beam, a compressed air cylinder for operating said means, and a valve controlling the pressure in the cylinder and operated by the movements of the tension lever.

5. In a loom, a warp beam, a tension lever 60 a worm connection between the tension lever and the warp beam, through which the tension lever may turn the warp beam back-

wardly, and means actuated by the movements of the tension lever for turning the worm.

6. In a loom, a warp beam, a tension lever, 70 a worm wheel on the warp beam, a worm connected with the tension lever and meshing with the worm wheel, fluid pressure-operated means for turning the worm, and a valve actuated by the movements of the tension lever for controlling the fluid pressure- 75 operated means.

7. In a loom, a warp beam, a tension lever, 80 a worm wheel on the warp beam, a worm meshing with the worm wheel and having swivel connection with the tension lever, a ratchet wheel carried by the worm, a swinging pawl engaging the ratchet wheel, fluid pressure means for swinging the pawl, and a valve operated by the movements of the tension lever for controlling the fluid pressure 85 means.

8. In a loom, a warp beam, a tension lever, 90 a worm wheel connected with the warp beam, a worm meshing with the worm wheel and having swivel connection with the tension lever, a ratchet wheel carried by the worm, a swinging pawl engaging the ratchet wheel, a compressed-air cylinder having its piston connected with the swinging pawl, a valve controlling the supply of compressed 95 air to the cylinder, and a trigger operated by the tension lever for controlling the valve.

9. In a loom, a warp beam, a tension lever 100 having connection with the warp beam, power-operated means operated by the movements of the tension lever for changing the position of the connection between the tension lever and the warp beam, and adjustable means for varying the degree of such 105 change.

10. In a loom, a warp beam, a tension lever, 110 a worm connection between the tension lever and the warp beam for turning the warp beam backwardly, power means operated by the movements of the tension lever for turning the worm, and adjustable means for varying the degree of movement imparted to the worm by the power means.

11. In a loom, a warp beam, a tension 115 lever, a worm wheel connected with the warp beam, a worm meshing with the worm wheel and connected with the tension lever, a ratchet wheel carried by the worm, a swinging pawl engaging the ratchet wheel, fluid 120 pressure-operated means for moving the swinging pawl, a valve operated by the movements of the tension lever for controlling the fluid pressure-operated means, and an adjustable stop for limiting the movements of the swinging pawl.

12. In a loom, a warp beam, a tension lever, 125 a worm wheel on the warp beam, a worm having swivel connection with the tension lever and meshing with the worm wheel,

bearings in which the worm is slidably mounted, a sleeve splined on the worm, a ratchet wheel fixed on the sleeve, a bell crank mounted on the sleeve, a pawl carried thereby meshing with the ratchet wheel, an adjustable stop mounted on a bearing and engaged by the bell crank, a cylinder with its piston connected with the bell crank, and means for controlling a supply of fluid pressure to the cylinder.

13. In a loom, a warp beam, a worm wheel thereon, a worm meshing with the worm wheel and slidably mounted in bearings, a tension lever with which the worm has a swivel connection, a compressed air cylinder, ratchet means operated by the movements of the piston thereof for turning the worm, a valve casing having connections with the cylinder and a source of compressed air supply and 15 provided with a valve seated between such

connections, a spring-pressed valve seated on the valve seat and provided with a tubular stem having an opening communicating with the cylinder connection, a roller connected with the tension lever, a bell crank 25 having a roller engaged by the first mentioned roller, a valve rod suspended from the bell crank, a yoke on the valve rod, a cup-shaped member seated in the yoke and receiving the tubular valve stem, and a valve 30 face in the cup-shaped member for closing the end of the tubular valve stem when the cup-shaped member is moved to force the valve off of its seat.

In testimony whereof I affix my signature 35 in presence of two witnesses.

ALBERT BERNARD WEISSENBORN.
